WIRE COUPLER

John P. Thompson, Portland, Oreg.

Application December 28, 1934, Serial No. 759,469

8 Claims. (Cl. 256—37)

This invention relates to devices for recoupling loose ends of wires under tension and is particularly useful in connection with wire fences.

An object of this invention is to provide a device in two parts of very low cost and small bulk but of great strength and efficiency whereby the user may attach one part to a severed wire and the other part to the other end of the severed wire, couple them together and bring the ends toward each other and restore tension.

Another object is a device whereby a farmer or stock man can insert an efficient gate in a wire fence, that may be opened and closed at will and that when closed will closely approximate the appearance and strength of the fence before the same was opened.

A still further object of this invention is to produce a device of the character described that may be inserted in a barbed wire fence and that will not appreciably diminish the efficiency of the fence with respect to repelling live stock.

The above objects and others which will be obvious to those skilled in the art to which this invention appertains are accomplished by the structure illustrated in the following drawings which accompany and form a part of this specification and in which,—

Fig. I is a partly sectionalized view of this new wire coupler illustrating its manner of construction and use as hereinafter more completely explained;

Fig. II is the same structure shown in Fig. I in a different position with respect to parts thereof and further illustrates its mode of operation;

Fig. III is an orthographic projection of Fig. I as it appears after locking as hereinafter described and with the pliers shown in dotted outline in Fig. I taken away;

Fig. IV is a section on IV—IV of Fig. I;

Fig. V is a section on V—V of Fig. I;

Fig. VI is a plan view of the sheet metal stamping which forms one part of the device without change, a section of which may be seen in Figs. IV and V;

Fig. VII is a plan view of the stamping which forms the other part of the device before it has been folded to its final shape as shown in Figs. I, II and III;

Fig. VIII is a view in which four of these devices, according to the invention, have been used to form a gate in a wire fence.

It will be observed in connection with this figure that the devices shown centrally disposed between the fence posts may be staggered so that they do not come opposite each other on a ver-

tical line and so that when applied to barbed wire, stock coming in contact with always feel one or more wires against their bodies.

The device consists of a stamping 1, as shown in Fig. VII, which is provided with a series of openings 2, on its axial line, a wire engaging loop 3, at one end, a slot 4, at the other end and a clip 5, at one side of the slot 4, and on the edge of the stamping.

This stamping is folded by a single operation 10 into the trough-like structure shown in the first five views, which is adapted to contain a slide 6, as shown in Fig. VI. The slide 6, is provided with a hook 7, near one end which is preferably undercut as shown and formed as a ratchet tooth as 15 shown in this view.

The slide 6 is provided with a loop 9 at the end opposite the hook 7, and is also provided with a lug 10 on its edge, opposite the said hook 7. The lug 10 is preferably formed as a notch such as 11 20 by providing another lug similar to 10, as indicated by numeral 12, and spaced from it.

The purpose of the slot 4 is to provide room for inserting the element 6 into the element 1 and bringing it into place and the purpose of the clip 25 5 is to retain the elements 1 and 6 in substantially longitudinal relationship when under stress as hereinafter described.

To use this device as a gate the wires of a wire fence will be cut and the element 1 wired by 30 means of the loop 3 to one cut end and the element 6 by means of the loop 9 will be wired to the other cut end. When it is desired to restore the fence and close the gate, the point 12 of element 6 is inserted through the slot 35 4 and the wire manually stretched as tight as may be convenient by bringing the two parts together and inserting the hook 7 in one of the openings 2. Afterwards a special pliers, such as that shown in dotted outline, is used by inserting 40 one leg in one of the openings 2 and the other leg behind the lug 10 and by a combined squeezing motion on the handles of the pliers and a rocking motion, the hook 7 is advanced successively from the opening 2 in which it was originally placed to succeeding openings until the desired tension is attained. This is an exceedingly powerful movement, of course depending somewhat upon the length of the jaws of the pliers used and its overall length, but by experiment it has been determined that an ordinary man using a pair of 9" pliers can strain a number 12 BWG soft steel wire beyond its elastic limit.

It will be noted that when tension is placed in the wire that the device securely locks itself in 55

- place and has no tendency to spring apart, but that it may readily be opened without any special tools by holding an object such as a field stone against the point indicated by the arrow *a*, and 5 tapping the hook *7* with another such object as indicated by the arrow *b*.

The openings *2* may be flared as at *2a* if preferred and by properly constructing the die with which these openings are formed this can be done 10 without extra cost.

Aside from its use in forming gates, its low cost, light weight and simplicity of application will permit it to be used in restoring tension in wires which have sagged, or wires that have become 15 broken may be fastened together easily and cheaply.

Having thus described and shown my invention so that anyone familiar with the arts to which it appertains can avail himself of its advantages, 20 what I claim as new and desire to secure by Letters Patent, is—

- 25 1. A wire coupler comprising a flat metal member folded to define three sides of a channel, ratchet openings in the central side, a retaining clip at one end and a wire loop at the other end, in combination with a ratchet hooked slide that is movable in the formed channel and adapted to be hooked from opening to opening in the first named member by application of leverage between the two members.
- 30 2. A wire coupler comprising a flat metal member folded to define three sides of a rectangular channel, ratchet openings in the central side, a retaining clip at one end and a wire loop at the other end, in combination with a ratchet hooked slide that is movable therein and adapted to be hooked from opening to opening in the first named member by application of leverage between the two members.
- 35 3. A wire coupler comprising a flat metal stamping folded to define three sides of a channel, a retaining clip over the fourth side at one end and a wire loop at the other end, ratchet openings in the central side of said channel and a co-oper-

ating slide member adapted to enter therein and be progressively locked thereto under the recurring application of leverage between the said slide and said formed channel.

4. In a wire coupler comprising a channel member and a co-operating slide member, ratchet openings in the channel member and an engaging hook on the slide member, the combination of an outflaring edge to constitute an inner sloping surface between ratchet openings in said channel 10 member.

5. In a wire coupling device a channel member that is provided with a slot at one end and a wire loop at the other end with a series of axially spaced ratchet openings therebetween, the same 15 being made from a single piece of sheet metal folded to define three channel boundaries, a wire loop at one end and a folded retaining clip opposite the slot at the end opposite the wire loop.

6. In a wire coupler, a slide member formed 20 from sheet metal, comprising a shank provided with a wire loop at one end thereof, an undercut projecting ratchet hook on one side near the other end and a leverage engaging lug opposite the said ratchet hook that is adapted to afford 25 a purchase of leverage for step by step advancement.

7. In a wire coupler comprising a channel member and a co-operating slide member, ratchet openings in the channel member, an engaging 30 hook on the slide member and means whereby leverage may be applied between the two members to advance the hook progressively with respect to the openings.

8. In a wire coupler comprising a channel mem- 35 ber and a co-operating slide member, wire engaging means on both members, ratchet openings in the channel member, an engaging hook on the slide member and means whereby leverage may be applied between the two members to pro- 40 gressively engage the hook with the said ratchet openings.

JOHN P. THOMPSON.
